UNITED STATES PATENT OFFICE.

LESTER A. LAWHEAD, OF ST. JOSEPH, MISSOURI.

RAILWAY-CROSSING SIGNAL.

1,418,660.

Specification of Letters Patent. Patented June 6, 1922.

Application filed July 6, 1920. Serial No. 394,166.

To all whom it may concern:

Be it known that I, LESTER A. LAWHEAD, a citizen of the United States, residing at St. Joseph, in the county of Buchanan and 5 State of Missouri, have invented new and useful Improvements in Railway-Crossing Signals, of which the following is a specification.

This invention relates to a new and useful 10 improvement in railway crossing signals and more particularly to those adapted for use at highway crossings or the like.

An object of this invention is to provide 15 a device of the character described which will be automatically operated by the approaching train, thus giving warning of the approach of the train to vehicles upon the highway in due time to permit said vehicles to wait until the train passes before attempting 20 to cross the track.

Another object of this invention is the provision of a signal, as hereinafter described, especially adapted for use in connection with single track railways and so constructed 25 to permit the operation of said signal by a train traveling in either direction upon said track.

A still further object of this invention is the provision of a signal adapted for single 30 track railways that will permit the passage of a train from either direction, giving warning automatically of its approach, through the medium of a plurality of treads and automatically resetting itself without 35 the need of additional levers or the like.

With the above and other objects in view, this invention resides in the novel features 40 of construction, formation, combination, and arrangement of parts to be hereinafter fully described, claimed and illustrated by the accompanying drawings, in which:

Figure 1 is a fragmentary top plan view of a sketch of single track illustrating my invention applied.

Fig. 2 is an enlarged sectional view of one 45 of the rails taken on line 2-2 of Fig. 1, illustrating in elevation the application of one of the treads thereto.

Fig. 3 is a perspective view of the rocker 50 arm, which carries the tread.

Fig. 4 is an enlarged side elevation of the cable draw bar.

Fig. 5 is a fragmentary longitudinal and 55 vertical sectional view through a portion of the road-bed of a railway with additional parts of the road-bed removed and parts of

the signal post broken away to illustrate clearly in elevation the parts which otherwise would be concealed.

Fig. 6 is an enlarged fragmentary vertical sectional view through the lower portion 60 of the signal posts.

Fig. 7 is a perspective view illustrating the assembly of one of the signal arm operating levers, and

Fig. 8 is a fragmentary front elevation of the upper portion of the signal post with parts broken away.

Referring to the accompanying drawings by similar characters of reference throughout, the numerals 10 and 11 denote treads, each of which are provided with shoulders 12 below which, at a suitable distance, they are pivotally connected as at 13 to a rocker arm 14. This rocker arm 14 has a suitable 70 offset portion 15 formed integral therewith to permit the treads 10 and 11 to operate freely without contacting with the head of the rail 16.

Passing through the rail 16 from the opposite side to that of the treads 10 and 11 is a draw bar 17 having a shoulder 18 formed integral therewith to limit its further passage therethrough, and is illustrated by the drawings, this draw bar 17 is 80 to be substituted for one of the customary bolts 18' ordinarily used to secure the fisher plates 19 in place to make a joint between two rails. One end of this draw bar 17 supports thereon the rocker arm 14 which is 90 held against displacement by the nut 20 while the opposite end thereof is offset as at 21 to engage a cable 22.

This cable 22 is suitably housed in a tubing 23 of any suitable construction, laid a 95 suitable distance below the surface of the earth or road bed and passes through to a signal post 24 composed of any suitable material with an anchor plate 25 formed integral therewith at the lower end thereof.

This signal post is substantially located, as illustrated by the drawings, a suitable distance from the railway track 26 at the side of a highway 27 and has pivotally mounted therein a plurality of levers 28 and 100 29, one end of which engage the cable 22, while their opposite ends engage flexible cables or the like 30. These levers 28 and 29 are held against longitudinal movement upon their supports 31 by washers 32 and 105 cotter pins 33, and likewise the supports 31 are held against longitudinal movement by 110

cotter pins 34. Thus, it will be readily seen that a free movement of said levers 28 and 29 is assured as desired, and that the undesired horizontal movement is limited.

5 The flexible cables or the like 30 are engaged at a suitable distance from the ends that engage the levers 28 and 29, by coil springs 35, suitably supported by a cross-rod 36 centrally and horizontally secured 10 within said signal post 24, while the opposite ends of said flexible cables engage substantially the inner end of a signal arm 36' pivotally secured to the outside of said signal post between brackets 37 and 38, be- 15 low which is substantially secured a bell 39, which will be sounded upon each downward stroke of the signal arm 36' through the medium of a bumper 40 carried thereby.

The operation of this device is simple and 20 as follows:

By referring to Figure 5 of the accompanying drawings, it will be readily understood that a train traveling in the direction of the arrows will first pass over the tread 25 11, and in so doing the flange of each wheel will first engage the tread 11 as indicated by the circle and tread shown in dotted lines, then as it passes thereover it will force downwardly the tread 11, as clearly illustrated by 30 the wheel indicated in full lines by the letter A, this movement of said tread as shown in full lines forces the rocker arm 14 in a downward direction, which being connected substantially with the draw bar 17, moves the 35 offset end 21 thereof in an upward direction, thus drawing the cable connected therewith through its housing, said cable being connected by levers to a second flexible cable, which in turn is connected at its opposite end 40 to the signal arm 36' will cause said arm to be raised to a horizontal position, as illustrated by this view; then as the wheel passes over and clears the tread, the arm will drop by gravity, all slack in the flexible cables 45 from its point of connection with the coil spring, being taken care of by said coil spring until the next set of wheels are passing over said tread; then the same operation is repeated, thus warning vehicles upon 50 the crossing thoroughfare in due time that a train is approaching and tolling the warning at every drop of the signal arm through the medium of the bell.

After the entire train has passed the road 55 way the wheels thereof will engage at a suitable distance up the track from the signal post the tread 10 which being pivotally secured to the rocker arm will swing upon its pivot, upon contact with each of said wheels, 60 a sufficient distance to clear the flange thereof so as to permit the wheels to pass thereover without operating the signal arm.

Trains traveling in the opposite direction will operate the signal in the same manner 65 by engaging the tread 10 first, the tread 11

will then be engaged and being pivotally secured to the rocker arm will swing upon its pivot until its shoulder 12 comes in contact with the rocker arm and when in this position the flange of the wheel will have forced 70 the tread 11 around on its pivot sufficient to permit said wheel to pass thereover without imparting sufficient pressure to the rocker arm to draw the cable connected therewith enough to operate the signal arm. It is to be 75 remembered that the tread 10 operates in a like manner when a train is traveling in the opposite direction thus providing a signaling device especially adapted for single track railways.

In connection with the above, it will be noted that these treads are constructed and so arranged that they may be operated by trains from either direction, but that only one of said treads will operate the signal 80 arm, and that tread is the first tread crossed by the train in its direction of travel, the other tread remaining neutral. Thus it is to be understood that the treads and their cooperating parts are all that is provided to 85 operate this signal and that the same are so applied to the rail so that repairs thereto may be readily made; likewise, the signal post is provided with suitable doors 41 to 90 permit repairing of any parts inclosed within 95 in said post.

The above description and operation of this device, together with the accompanying drawings is thought to be sufficient to enable those familiar with this art to readily understand the construction, operation and many advantages of this invention. It should be understood, however, in this connection, that various minor changes in the details of construction may be resorted to within the 100 scope of the appended claims, without departing from or sacrificing any of the advantages of this invention.

From the foregoing disclosure, taken in connection with the accompanying drawings, it will be manifest that I have provided a railway crossing signal, especially adapted for use where a railway crosses a highway, which is simple in construction and operation, and which will fulfill all of the necessary requirements of such a device.

Having thus fully described this invention, what I claim as new and desire to protect by Letters Patent is:

1. A signal comprising a post, a movable 120 signal arm secured thereto, a plurality of treads substantially secured to a rail, means connecting each of said treads with the signal arm, a warning signal secured to said post, a member carried by the movable signal arm and adapted to engage at intervals said warning signal, and means for permitting the independent operation of each of said treads.

2. A signal comprising a post, a movable 130

arm secured thereto, a plurality of flexible members having one of their ends secured to said movable arm, a plurality of movable levers mounted within said post and engaging the other ends of the flexible members, 5 a coil spring engaging each of said flexible members and secured within said post, a

cable engaging each of said movable levers, a tread connected with each of said cables, and means for permitting the independent 10 operation of each of said treads as means for moving said movable arm.

LESTER A. LAWHEAD.
